[57] CLAIM

The ornamental design for a display apparatus for electronic calculator, as shown and described.

DESCRIPTION

FIG. 1 is a front elevational view of a display apparatus for electronic calculator showing my new design;

FIG. 2 is a rear elevational view thereof;

FIG. 3 is a top plan view thereof;

FIG. 4 is a bottom plan view thereof;

FIG. 5 is a side elevational view as seen from the left of FIG. 1; and

FIG. 6 is a perspective view of the display apparatus for electronic calculator.

The side elevational view as seen from the right of FIG. 1 is omitted as it is symmetrical with the side elevational view as seen from the left of FIG. 1.

FIG. 1

FIG. 2

FIG. 3

FIG. 4

FIG. 5

FIG. 6
